TOY AUTOMOBILE OR SIMILAR ARTICLE

James Lee Kirkpatrick, 8221 Ilex St., Fontana, Calif.

Filed July 6, 1964, Ser. No. 80,708

Term of patent 14 years

(Cl. D34—15)

FIGURE 1 is a perspective view of a toy automobile or similar article, embodying the design of the invention;

FIGURE 2 is a front elevational view of the toy automobile or similar article, shown in FIGURE 1;

FIGURE 3 is a top plan view of the toy automobile or similar article, shown in FIGURE 1;

FIGURE 4 is a right-side, elevational view of the toy automobile or similar article, shown in FIGURE 1; and

FIGURE 5 is a rear elevational view of the toy automobile or similar article, shown in FIGURE 1.

I claim:

The ornamental design for a toy automobile or similar article, as shown.
